(57) **CLAIM**

The ornamental design for a produce tray, as shown and described.

DESCRIPTION

FIG. 1 is top right perspective view of an ornamental design for a produce tray showing our new design in use to hold an apple when horizontally stacked in a box with other produce trays;

FIG. 2 is a left side view of the produce tray of FIG. 1, with the produce tray oriented in a vertical position with respect to the box and other produce trays;

FIG. 3 is a top right perspective view of the produce tray; FIG. 4 is a bottom left perspective view thereof;

FIG. 5 is a front elevational view of thereof, the rear side of the produce tray being a mirror image thereof;

FIG. 6 is a right side elevational view thereof;

FIG. 7 is a left side elevational view thereof;

FIG. 8 is a top plan view thereof; and,

FIG. 9 is a bottom plan view thereof.

In FIG. 1, the broken lines show an apple, an additional produce tray and a box, and in FIG. 2, the broken lines show a box and additional produce trays that depict environment that forms no part of the claimed design; all other broken lines in the drawings show portions of the produce tray that form no part thereof. The produce tray is shown with a symbolic break in its length. The appearance of any portion of the produce tray between the break lines forms no part of the claimed design.
